Primary Examiner—Gary D. Watson
Attorney, Agent, or Firm—David H. Semmes**[57] CLAIM**

The ornamental design for a folding beach chair, as shown and described.

DESCRIPTION

FIG. 1 is a perspective view of the folding beach chair in unfolded position;

FIG. 2 is a side elevational view, the opposite side being substantially a mirror image thereof except for the position of the rear pouches;

FIG. 3 is a front elevation;

FIG. 4 is a rear elevation;

FIG. 5 is a top plan;

FIG. 6 is a bottom plan, and,

FIG. 7 is a perspective view of the folding beach chair in folded position.

The fragmented broken line showing of a carrying strap is for environmental purposes only and forms no part of the claimed design.
